DESIGN FOR A MILKING MACHINE CLAW

Gustave A. Anderson, Chicago, Ill.

Application May 28, 1945, Serial No. 119,758

Term of patent 14 years

(Cl. D23—1)

To all whom it may concern:

Be it known that I, Gustave A. Anderson, a citizen of the United States, residing at Chicago, in the county of Cook and State of Illinois, have invented a new, original, and ornamental Design for a Milking Machine Claw, of which the following is a specification, reference being had to the accompanying drawing, forming a part thereof.

Figure 1 is a plan view of a milking machine claw, showing my new design;

Figure 2 is a bottom view thereof;
Figure 3 is a side view thereof;
Figure 4 is a view of the right hand end thereof; and
Figure 5 is a view of the left hand end thereof.
I claim:
The ornamental design for a milking machine claw, substantially as shown.

GUSTAVE A. ANDERSON.
